ELECTRICAL SWITCH

George W. Goldner, St. Louis, Mo., assignor to
 James R. Kearney Corporation, St. Louis, Mo.,
 a corporation of Missouri

Application April 12, 1939, Serial No. 267,370

9 Claims. (Cl. 200—146)

This invention relates generally to electrical switches and more specifically to electrical switches of the by-pass, disconnect type, the predominant object of the invention being to provide a novel, efficiently operating switch for manually by-passing or removing load from electrical equipment such, for instance, as, induction regulators, step voltage regulators, booster transformers, and current transformers of primary metering equipment, while inspections and adjustments are being made.

The improved switch disclosed herein is embodied in unitary form and an important feature thereof is that it is operable to perform four distinct switching operations in succession during a single operation of the switch. In other words when the improved switch is operated to take a regulator or other piece of equipment out of service, the regulator is first bypassed, then the two main switch blades are withdrawn from their contacts, after which the switch operates to interrupt passage of exciting current to the regulator. In an equivalent installation employing conventional switches for taking a regulator out of service, three switches and a small manually operated circuit breaker for interrupting exciting current, are required for each regulator. Therefore during a single operation of the improved switch disclosed herein in the switching duties of four independent switches of the conventional installation are performed.

Fig. 1 is a side elevation of the improved switch disclosed herein.

Fig. 2 is a front elevation of the switch illustrated in Fig. 1.

Fig. 3 is a fragmentary vertical section on an enlarged scale, illustrating the mechanism which serves to interrupt exciting current when the improved switch is operated.

Fig. 4 is a horizontal section taken on line 4—4 of Fig. 2, looking in the direction indicated by the arrows.

Fig. 5 is a horizontal section taken on line 5—5 of Fig. 2, looking in the direction indicated by the arrows.

Fig. 6 is a fragmentary section illustrating the upper portion of the switch in a partially opened condition.

Fig. 7 is a side elevation of the switch, on a reduced scale, showing the switch as it appears as it approaches the fully open position.

Fig. 8 is a circuit diagram illustrating the improved switch arranged in electrical connection with an induction-type regulator.

In the drawings, wherein is shown for the purpose of illustration, merely, one embodiment of the invention, A designates the improved switch generally. The particular switch illustrated in the drawings includes a pair of spaced insulators B which are fixed to a suitable support C as shown in Figs. 1 and 2. Secured to the lower insulator B by means of suitable fastening elements 1 is a member 2, said member 2 being provided with an outwardly extended, vertically disposed portion 2a at its approximate center to which an angular element 3 is secured by one of the fastening elements 1 which secure the member 2 to the lower insulator, so that said angular element is disposed with one of its legs extended vertically and its other leg extended horizontally. Secured to the member 2 is a pair of downwardly extended terminals 4 and 5 in the form of bars, said terminals being interposed at their upper ends between bosses formed on the member 2 and inwardly turned ears 6 of bearing members 6, and said terminal members and said bearing members being secured to the member 2 by fastening elements 7 (Fig. 5) which are anchored to said member 2 and pass through the terminal members and the ears of the bearing members. The bearing members are spaced apart as shown to the best advantage in Figs. 2 and 5 and said bearing members are provided with openings 6a formed in their outer end portions which are intended to serve a function to be hereinafter set forth. The terminals 4 and 5 have connected thereto at their lower ends, through the instrumentality of suitable connectors 8, electrical conductors, the conductor connected to the terminal 4 being designated by the reference character D, and the conductor connected to the terminal 5 being designated by the reference character E. The conductors D and E lead from the switch A to the piece of electrical equipment with which the switch is electrically associated.

The improved switch disclosed herein includes two spaced apart switch blades 10 and 11 which are secured together by means of a plurality of insulating blocks 12 which are interposed between said switch blades and are secured thereto by fastening elements 12'. The switch blade 10 at its lower end is provided with an inwardly turned portion 10' (Fig. 2) which, when the switch blades are drawn outwardly and downwardly contacts with the horizontal leg of the angular element 3 to limit downward movement of said switch blades. The switch blades 10 and 11 are provided with trunnions 13 which are se-

cured by riveting, or otherwise, to the switch blades and are provided with portions 13' of reduced diameter which are disposed in the openings 6a of the bearing members 6. By this means the switch blades are supported by the bearing members for hinged or pivotal movement with respect to said bearing members, the trunnions rotating with the switch blades during movement thereof. In order to make good electrical contact between the terminals 4 and 5 and the trunnions 13 of the switch blades groups of resilient contact elements 14 are provided. These groups of contacts comprise assemblies of lengths of relatively heavy wire which are suitably anchored to the terminals 4 and 5 and bear with considerable compressive force at their outer ends against opposite portions of the trunnions of the switch blades.

Referring now to the upper end of the switch A, the upper insulator B has secured thereto a member 15 which resembles the member 2 heretofore described as being associated with the lower insulator B. The member 15 is provided with a raised portion 15' which extends vertically at the approximate center of said member and the vertical leg 16' of a keeper 16 is arranged in longitudinal contact with said raised portion. In order to secure said keeper 16 and said member 15 to the upper insulator B a pair of fastening elements 17 are extended through said keeper and member and pass into said upper insulator. The keeper includes an upwardly inclined portion 16a, which extends from the upper end of the vertical leg of said keeper, and at the outer end of this inclined portion a head 16c is provided, said head having an extension 16d formed thereon which serves a purpose to be hereinafter set forth. The member 15 has also secured to it by fastening elements 18' a pair of terminals 18 and 19, and these terminals have connected to them, by means of suitable connectors 20, electrical conductors D' and E' which lead to the switch from a source of electrical energy.

At the upper end of the switch, opposed contact assemblies 21 and 22 are provided, into and out of contact with which the switch blades 10 and 11 are movable. Each of these contact assemblies comprises a plurality of lengths of relatively heavy resilient wire shaped in plan as shown in Fig. 4; that is to say the lengths of wire of the opposed contact assemblies include rear portions 22a which are suitably anchored to the terminals 18 and 19 and extend outwardly therefrom, convergent portions which extend from the forward ends of the rear portions 22a, parallel portions 22c with which the switch blades are adapted to contact, and flared portions 22d which extend outwardly from said portions 22c. By referring to Fig. 2 it will be noted that the switch blade 10 is provided at its upper end with an extension 23 which extends inwardly at an upwardly extended angle to the approximate center of the dual blade structure and upwardly beyond said angularly extended portions. Mounted at the upper end of this extension is a latch 24 which is pivoted at 25 to the extension 23, said latch being bifurcated in part so that the extension 23 of the switch blade is located between spaced portions of the latch, and the pivot 25 being extended through said spaced portions and through the extension 23. The latch has associated with it a torsional coil spring 26 which is coiled about the opposite ends of the pivot 25 and extends over the top of the latch in contact therewith. The ends of the torsional coil spring

are anchored at opposite sides of the extension 23 to a pin 27 which is supported by said extension 23, said pin 27 serving also as a pivot for a latch operating device 28 which includes an operating ring 28a and nubs 28b at opposite sides of the extension 23 that contact with the latch 24. The latch operating device 28 includes a bifurcated portion in which a portion of the extension 23 is disposed and the face 28c at the base of the bifurcated portion of the latch operating device is adapted to contact with the forward face of the extension 23 when the ring 28a is pulled downwardly to limit movement of said latch operating device with respect to said extension.

When, in the operation of the switch disclosed herein, the switch blades are moved upwardly from the open switch position to the closed switch position, the switch blades move into contact with the flared portions 22d of the opposed contact assemblies 21 and 22 and said portions 22c of the opposed contact assemblies bear with considerable force against the switch blades when the closed switch position is reached by the switch blades. Also as the switch blades approach the closed switch position the nose portion 24' of the latch 24 rides up the inclined face 16e of the keeper 16 against the force of the torsional coil spring 26 until said nose portion passes beyond the extension 16d of said keeper at which time the torsional coil spring 26 moves the nose portion of the latch downwardly behind the extension 16d of the keeper to lock the switch blades in the closed switch position as shown in Fig. 1. When it is desired to move the switch blades from the closed switch position to the open switch position the ring 28a of the latch operating device is pulled downwardly. This causes the nubs 28b of the latch operating device to move the lower end portion of the latch rearwardly and thereby elevate the nose portion of said latch out of engagement with the extension 16d of the keeper 16. Such movement of the latch operating device brings the lower portion of the face 28c into contact with the forward face of the extension 23 of the switch blade 10 and a continued outward and downward pull exerted on the ring of the latch operating device will draw the switch blades out of contact with the opposed contact assemblies 21 and 22.

Pivotedly supported by the keeper 16 at the point designated by the reference character 29 is a by-pass blade 30, said by-pass blade being bifurcated at its upper end as shown in Fig. 2 to provide spaced portions which are disposed at opposite sides of the head 16c of the keeper and which are pivotally attached to said keeper head by the pivot 29. The lower portion of the by-pass blade is of greater width than the upper bifurcated portion thereof so that said wider lower blade portion may be drawn between and in electrical contact with the portions 22c of the opposed contact assemblies 21 and 22. The wider lower portion of the by-pass blade 30 has an opening 31 formed therein and secured to a face of said wider lower portion of the by-pass blade is a plate 32 which overhangs said opening as shown in Fig. 6. The by-pass blade 30 has a torsional spring 30' associated therewith which tends to urge the lower end of said blade outwardly. The torsional spring 30' has portions coiled about the pivot element 29 at opposite sides of the blade with the opposite ends of the spring seated in apertures formed in the blade

and a bridge portion of the spring engaging a portion of the keeper 16.

Secured to the switch blade 10 is a member 33 which is provided with an extension 33', said extension being adapted to move into and out of the opening 31 formed in the by-pass blade 30 during certain phases of the operation of the improved switch. The extension 33' of the member 33 is provided with an opening 34 formed therein and arranged in this opening is an element 35 which is mounted for movement with respect to said extension 33' by a pivot 36. As shown to the best advantage in Fig. 6 the element 35 is adapted to engage the portion of the plate 32 which overhangs the opening 31 so that when the switch blades 10 and 11 are drawn outwardly out of contact with the contact assemblies 21 and 22, the lower portion of the by-pass blade will also be drawn outwardly, because of engagement between the element 35 and the plate 32, to move said lower wider portion of the by-pass blade into contact with the portions 22c of the contact assemblies 21 and 22.

The element 35 at its lower forward end contacts with the face 34' of the opening 34 formed in the extension 33' of the member 33, and this arrangement prevents rearward rotation of the upper portion of said element 35 when the lower portion of the by-pass blade is being drawn forwardly during outward movement of the switch blades 10 and 11 by contact between said upper portion of the element 35 and the plate 32 of the by-pass blade. Also the member 33 has fixed to it a flat spring 37 which contacts at its free rearward end with the lower face of the element 35 (Fig. 6). Because of this arrangement the element 35 may rotate forwardly at its upper end to permit the upper end of the element 35 to ride beneath the plate 32 and snap into a position behind the lower portion of said plate when the switch blades are being moved to the closed switch position. In order to move the by-pass blade rearwardly when the switch blades 10 and 11 are being moved to the closed switch position, the extension 33' is provided with a pair of oppositely extending pins 38 which contact with portions of the by-pass blade at opposite sides of the opening 31, as the switch blades approach the closed switch position, and thereby move the by-pass blade rearwardly with the rearwardly moving switch blades 10 and 11. Thus as the switch blades move into contact with the portions 22c of the contact assemblies 21 and 22 when the switch is being closed, the by-pass blade will be moved out of contact with said contact portions 22c to a position rearwardly thereof where the elements of the opposed contact assemblies 21 and 22 are so widely separated that the by-pass blade will not contact therewith.

For the purpose of limiting forward movement of the by-pass blade 30 the head 16c of the keeper 16 is provided with an abutment 39 with which an upper portion of the by-pass blade contacts when the forward limit of movement of said by-pass blade has been reached. This forward limit of movement of the by-pass blade is attained at the moment the plate 32 of the by-pass blade reaches such elevation, during forward movement of the by-pass blade, that the upper portion of the element 35 may pass beneath said plate 32 to effect disengagement of the element 35 and the plate 32.

Supported by the switch blade 10 of the improved switch is an auxiliary switch 40 for interrupting passage of exciting current to a piece of 75

equipment with which the improved switch A is associated. The auxiliary switch 40 comprises a stud shaft 41 (Fig. 3) which includes a screw-threaded end portion 41' that is extended through an opening formed through the switch blade 10 and receives a nut 42 for securing said stud shaft to said switch blade. Mounted on the stud shaft 41 is a member 43, formed of electrical conducting material, which includes a horizontal tubular portion 44 and a tubular portion 45 which is extended at an approximate right angle with respect to said horizontal tubular portion. The horizontal tubular portion 44 of the member 43 embraces the stud shaft 41, a pin 46 being supported by the wall of said horizontal tubular portion and being extended into an annular groove 46' formed in the stud shaft, so as to permit rotary movement of the horizontal tubular portion with respect to the stud shaft while preventing longitudinal movement of the horizontal tubular portion relative to the stud shaft.

Extended through and supported by the tubular portion 45 of the member 43 is a tube 47 which may be made of Bakelite or other suitable insulating material. The tube 47 has arranged in the lower portion thereof in contact with the inner face of the tube a metallic tubular contact 47', the lower edge of said tubular contact 47' being flush with the lower edge of the tube 47, and said tubular contact 47' at its upper end being provided with a plurality of upwardly extended, integral fingers 48. As shown in Fig. 1, the tube 47 and the tubular contact 47' arranged therein are secured together and are attached to the tubular portion 45 of the member 43 by a metallic rivet 43', and this rivet serves also as a conductor for electrically connecting the tubular contact to the member 43. Arranged within the upper portion of the tube 47 is an inner tube 49 formed preferably of fiber, said inner tube 49 being suitably secured in place within the outer tube 47. The inner tube 49 is internally screw-threaded at its upper end and screwed in this internally screwthreaded portion of said inner tube is an externally screwthreaded sleeve 50. Also cemented, or otherwise secured to the top edges of the outer tube 47, the inner tube 49, and the sleeve 50 is a washer 51 formed of rubber or other yieldable material.

Located within the tube 47 is a rod 52 which is provided at its upper end with a screwthreaded extension 53 of reduced diameter. This screwthreaded extension is screwed into an opening 54 formed in a cap 55 which normally embraces the upper end portion of the tube 47 and is provided with an upstanding finger 56, said finger being provided with an annular groove 56'. The rod 52 extends downwardly from cap 55, passing through the sleeve 50, and mounted on the lower portion of said rod, which is of reduced diameter, is a tubular contact element 57 with which the fingers 48 of the tubular contact 47' are adapted to contact as shown in Fig. 3. The tubular contact 57 is in engagement with a shoulder 58 formed on the rod 52 where the reduced lower portion of said rod meets the upper rod portion of larger diameter, and mounted on the extreme lower end portion of said rod is a fiber tube 59 whose upper edge contacts with the lower edge of the tubular contact 57. The fiber tube 59 is secured to the rod 52 by a pin 60, and arranged within the fiber tube 59 is an inner tube 61 formed preferably of Bakelite which is disposed beneath the lower end of the rod 52 and is suitably secured in place within the fiber

tube 59. Interposed between the lower face of the sleeve 50 and the top face of the tubular contact 57 is a coil spring 66 which surrounds the rod 52.

Arranged about the tubular portion 44 of the member 43 is a torsional coil spring 62 one end of which is anchored to the switch blade 10 as indicated at 62a and the opposite end of which is anchored to the member 43 as indicated at 62b. The torsional coil spring tends to move the auxiliary switch 40 to a position where it is parallel, mechanically, with respect to the switch blade 10 as shown in Fig. 1, said switch blade 10 being provided with a member 63 which is provided with a curved seat, as shown to the best advantage in Fig. 4, that is adapted to receive and hold the auxiliary switch in such position in parallelism with respect to the switch blade 10. Anchored in the terminal 18 is a contact 64 comprised of a pair of resilient, spaced apart contact elements which are flared apart at their outer ends as indicated at 64' in Fig. 4, said spaced apart contact elements being provided with an embracing band 65 which prevents undue spreading of said contact elements. In the closed position of the switch A the finger 56 at the upper end of the auxiliary switch 40 is positioned between the spaced contact elements of the contact 64 with said spaced contact elements seated in the annular groove 56' of said finger as shown to the best advantage in Fig. 3. Also as will presently appear herein the finger 56 of the auxiliary switch 40 is withdrawn from contact with the contact 64 during a certain phase of the operation of the switch A.

In describing the operation of the improved switch A, it will be assumed that the switch is in the closed switch position as shown in Fig. 1. In this position of the switch electrical energy is conducted from a source of energy to the terminal 18 by the conductor D', said energy then passing through the contact assembly 21 to the switch blade 10, from the trunnions 13 of the blade 10 by way of the contact assembly 14 to the terminal 4, and to the equipment with which the switch is electrically associated by way of the conductor D. The path of electrical energy from the equipment is by way of the conductor E, terminal 5, contact 14, switch blade 11, contact 22, terminal 19 and conductor E'. Also, part of the current, which is conducted to the terminal 18, passes through the contact 64 to the cap 55 of the auxiliary switch 40, through the rod 52 to the tubular contact 57, through the fingers 48 and tubular contact 47 to the switch blade 10 by way of the rivet 47' and the member 44, and from the switch blade to the equipment with which the switch is associated by way of the terminal 4 and conductor D.

Assume now that it is desired to take the equipment with which the switch is associated out of service for inspection or repairs. In this event the ring 28a of the latch operating device 28 is pulled downwardly to raise the nose portion 24' of the latch 24 out of engagement with the extension 16d of the keeper 16. This movement of the latch operating device causes the face 28c of the latch operating device to contact with the outer face of the extension 23 of the switch blade 10 and continued outward and downward pull on the ring of the latch operating device will move the upper portions of the switch blades 10 and 11 outwardly with respect to the contact assemblies 21 and 22. The element 35 carried by the member 33 secured to the switch blade 10 is in engagement with the plate 32 of the by-pass blade 30

as shown to the best advantage in Fig. 6, and therefore as the switch blades 10 and 11 are drawn outwardly the lower portion of the by-pass blade 30 will likewise be drawn outwardly into a position between and in electrical contact with the portions 22c of the contact assemblies 21 and 22. The by-pass blade is moved into contact with the portions 22c of the contact assemblies immediately before the switch blades 10 and 11 move out of contact with said contact portions 22c, and as soon as contact is made between the by-pass blade and the contact portions 22c the current is by-passed across the contact assemblies 21 and 22. As the outward movement of the switch blades 10 and 11 continues the lower end portion of the by-pass blade 30 reaches an outward point where the abutment 39 arrests forward movement of the lower portion of the by-pass blade and at this time the lower edge of the plate 32 of said by-pass blade has reached an elevation where the upper portion of the element 35 may pass under said plate 32 so as to disengage said element 35 from said plate 32.

During the outward movement of the switch blades 10 and 11 thus far described, the auxiliary switch 40 for interrupting passage of exciting current to the equipment with which the switch A is associated is in electrical connection with the contact 64, and therefore exciting current continues to flow to the equipment through the path previously described herein. As a result of the fact that exciting current continues to flow to the equipment associated with the switch A, arcing is eliminated when the switch blades 10 and 11 are drawn out of contact with respect to the contact assemblies 21 and 22. As downward movement of the switch blades 10 and 11 continues, the tube 47 of the auxiliary switch 40 together with the parts assembled therewith, move downwardly with respect to the rod 52, which, as shown in Fig. 7, is still connected to the contact 64, and eventually during such downward movement of the tube 47, the fingers 48 of the tubular contact 47' of the auxiliary switch 40 move out of contact with respect to the tubular contact 57 supported by the rod 52. This interrupts passage of exciting current to the equipment and arcs which are produced when electrical contact is broken between the contact fingers 48 and the contact 57 are drawn between the fiber tube 49 which moves downwardly with the tube 47 and the stationary fiber tube 59 which is fixed to the rod 52, the arcs being effectively extinguished between said tubes because the tubes 49 and 59 are formed of horn fiber which is characterized by the ability to give off gas in the presence of an electric arc which tends to extinguish the arc. The exciting current interruption is started in the manner described when the switch blades 10 and 11 have moved a sufficient distance from the contact assemblies 21 and 22 to prevent arcing at said contact assemblies.

As downward movement of the switch blades continues, the arc path between the contact fingers 48 and the contact 57 is elongated and the arc is extinguished. Then, as downward movement of the blades continues further, and after the exciting current has been interrupted as explained, the finger 56 of the cap 55 will be disengaged from the contact 64 by being drawn beyond the outer end thereof. When this happens the coil spring 66 which is compressed between the top edge of the contact 57 and the bottom face of the sleeve 50 when the tube 47 is moved longitudinally with respect to the rod 52,

will expand thereby moving the rod 52 downwardly into the tube 47 to the position of these parts as shown in Fig. 3, and at about the same time the torsional coil spring 62 will swing the auxiliary switch 40 to a position in parallelism with respect to the switch blade 10 as has already been explained herein.

To replace the equipment with which the switch A is associated in service the switch blades are moved upwardly into contact with the portions 22c of the contact assemblies 21 and 22 and at the same time the by-pass blade 30 will be moved rearwardly by the member 33 of the blade 10 out of contact with said contact portions 22c, the finger 56 of the tubular switch 40 will be moved into engagement with the contact 64, and the switch blades 10 and 11 will be latched in the closed switch position. This arrangement completely restores the equipment with which the switch A is associated in service for normal operation.

It is obvious, therefore, as previously stated herein, that a single operation of the switch from the closed to the open position accomplishes four distinct switching operations in succession; that is to say during such single operation of the switch the equipment with which the switch is associated is first by-passed, the main switch blades 10 and 11 are then withdrawn from the contact assemblies 21 and 22 and the auxiliary switch 40 operates to interrupt the exciting current.

It is pointed out that the switch disclosed herein may be used without the auxiliary switch 40 being a part thereof, in which event, if necessary, a separate manually operated circuit breaker would be employed to interrupt the exciting current. In this case a single operation of the switch will by-pass the current and withdraw the main switch blades from their contacts, a separate operation being required to interrupt the exciting current.

In Fig. 8 a circuit diagram is illustrated showing the improved switch arranged in electrical connection with an induction-type regulator R. In this view P designates the primary winding of the regulator R, and S designates the series winding thereof. Also, in Fig. 8 are shown diagrammatically the switch blades 10 and 11, the by-pass blade 30, and the auxiliary switch 40 of the improved switch. Additionally, Fig. 8 illustrates conductors W^a, W^b, W^c, W^d and W^e which serve, in an obvious manner, to interconnect the switch and the regulator electrically and to connect the switch and regulator with a primary 55 feeder P'.

I claim:

1. A disconnect switch comprising spaced contacts, a blade structure comprising a pair of blades supported for movement into and out of electrical contact with said spaced contacts, a by-pass member supported independently of said blade structure for pivotal movement into electrical contact with said spaced contacts so as to by-pass electrical energy from one to the other of said spaced contacts and out of such electrical contact with said spaced contacts, said blade structure being adapted for movement independently of said by-pass member, and means carried by said blade structure and adapted to engage said by-pass member whereby movement of said blade structure to draw the pair of blades thereof out of electrical contact with said spaced contacts will move said by-pass member into electrical contact with said spaced contacts.

2. A disconnect switch comprising spaced contacts, a blade structure comprising a pair of blades supported for movement into and out of electrical contact with said spaced contacts, a by-pass member supported independently of said blade structure between said spaced contacts for movement into electrical contact with portions of said spaced contacts so as to by-pass electrical energy from one to the other of said spaced contacts and out of such electrical contact with said spaced contacts, said blade structure being adapted for movement independently of said by-pass member, and means carried by said blade structure and adapted to engage said by-pass member whereby movement of said blade structure to draw the pair of blades thereof out of electrical contact with said spaced contacts will move said by-pass member into electrical contact with said portions of said spaced contacts.

3. A disconnect switch comprising spaced contacts, a blade structure comprising a pair of blades supported for movement into and out of electrical contact with said spaced contacts, said spaced contacts including portions which are widely spaced apart and portions which are relatively close together, a by-pass member supported between said widely spaced portions of said spaced contacts where it is normally out of electrical contact with said spaced contacts and adapted for movement into electrical contact with said relatively close portions of the spaced contacts so as to by-pass electrical energy from one to the other of said spaced contacts, and means carried by said blade structure and adapted to engage said by-pass member whereby movement of said blade structure to draw the pair of blades thereof out of electrical contact with said spaced contacts will move said by-pass member into electrical contact with said closely spaced portions of said spaced contacts.

4. A disconnect switch comprising spaced contacts, a blade structure comprising a pair of blades supported for movement into and out of electrical contact with said spaced contacts, said spaced contacts including portions which are widely spaced apart and portions which are relatively close together, a by-pass member supported between said widely spaced portions of said spaced contacts for movement into electrical contact with said relatively close portions of the spaced contacts so as to by-pass electrical energy from one to the other of said spaced contacts, manually operated latch means carried by said blade structure, a keeper into engagement with which said latch means is movable to lock the blades of the blade structure in contact with said spaced contacts, means for pivotally attaching said by-pass member to said keeper, and means carried by said blade structure and adapted to detachably engage said by-pass member whereby movement of said blade structure to draw the pair of blades thereof out of electrical contact with said spaced contacts will move said by-pass member into electrical contact with said closely spaced portions of said spaced contacts.

5. A disconnect switch comprising spaced contacts in the form each of a plurality of assembled resilient contact elements, a blade structure comprising a pair of blades supported for movement into and out of electrical contact with said spaced contacts, said spaced contacts including portions which are widely spaced apart and portions which are relatively close together, a by-pass member supported between said widely spaced

portions of said spaced contacts for movement into electrical contact with said relatively close portions of the spaced contacts so as to by-pass electrical energy from one to the other of said spaced contacts, manually operated latch means carried by said blade structure, a keeper into engagement with which said latch means is movable to lock the blades of the blade structure in contact with said spaced contacts, means for pivotally attaching said by-pass member to said keeper, and means carried by said blade structure and adapted to detachably engage said by-pass member whereby movement of said blade structure to draw the pair of blades thereof out of electrical contact with said spaced contacts will move said by-pass member into electrical contact with said closely spaced portions of said spaced contacts.

6. A disconnect switch comprising spaced contacts, a blade structure comprising a pair of blades supported for movement into and out of electrical contact with said spaced contacts, a by-pass member movable into contact with said spaced contacts in response to movement of the pair of blades of said blade structure out of contact with said spaced contacts so as to by-pass electrical energy from one to the other of said spaced contacts, an auxiliary switch operated in response to movement of the blades of said blade structure out of contact with said spaced contacts to interrupt exciting current which passes through said auxiliary switch when said blades of the blade structure are withdrawn from contact with said spaced contacts, and a contact into and out of electrical contact with which said auxiliary switch moves in response to movement of said blade structure, said auxiliary switch comprising relatively movable portions one of which is normally mechanically connected to the last mentioned contact and adapted for release therefrom and the other of which is connected to said blade structure for independent movement with respect thereto, and the switch portion connected to said blade structure being movable with said blade structure and with respect to the associated switch portion, when said blade structure is moved to the open switch position, to interrupt an electrical path through the auxiliary switch.

7. A disconnect switch comprising spaced contacts, a blade structure comprising a pair of blades supported for movement into and out of electrical contact with said spaced contacts, a by-pass member movable into contact with said spaced contacts in response to movement of the pair of blades of said blade structure out of contact with said spaced contacts so as to by-pass electrical energy from one to the other of said spaced contacts, an auxiliary switch operated in response to movement of the blades of said blade structure out of contact with said spaced contacts to interrupt exciting current which passes through said auxiliary switch when said blades of the blade structure are withdrawn from contact with said spaced contacts, a contact into and out of electrical contact with which said auxiliary switch moves in response to movement of said blade structure, said auxiliary switch comprising relatively movable portions

one of which is detachably connected to the last-mentioned contact and the other of which is pivotally connected to said blade structure, and the switch portion connected to said blade structure being movable with said blade structure and with respect to the associated switch portion, when said blade structure is moved to the open switch position, to interrupt an electrical path through the auxiliary switch, and means comprising a torsional coil spring arranged at the pivotal connection between said auxiliary switch and said blade structure for moving the auxiliary switch to a predetermined position with respect to said blade structure when said auxiliary switch is detached from its contact.

8. A switch comprising a tube formed of insulating material which is supported for pivotal movement, a rod disposed within said tube for movement longitudinally thereof, said tube and rod being adapted for relative longitudinal movement, a spring located within said tube which tends to restore said tube and rod to predetermined relative positions when said tube and rod have been subjected to relative movement, a contact carried by said rod, a second contact fixed to said tube within same, the tube and rod being movable with respect to each other to position said contacts in electrical contact with each other to provide an electrical path through the switch and to separate said contacts to break such electrical path, a tubular element fixed within said tube, and a tubular member secured to said rod, said tubular element being moved into embracing relation with respect to said tubular member when the tube and rod are subjected to relative movement to separate the contacts whereby an electrical arc produced when the contacts are separated is drawn between the walls of said tubular element and tubular member, said tubular element and said tubular member being formed of a material characterized by the ability to give off gas in the presence of an electric arc which acts to extinguish said arc.

9. A disconnect switch comprising spaced contacts, a blade structure comprising a pair of blades supported for movement into and out of electrical contact with said spaced contacts, a by-pass member supported for movement into electrical contact with said spaced contacts so as to by-pass electrical energy from one to the other of said spaced contacts and out of such electrical contact with said spaced contacts, said blade structure being adapted for movement independently of said by-pass member, and means carried by said blade structure adapted to engage said by-pass member for subjecting said by-pass member to movement, said by-pass member being movable into electrical contact with said spaced contacts in response to movement of said blade structure which withdraws said blade structure from electrical contact with said spaced contacts and being movable out of electrical contact with said spaced contacts in response to movement of said blade structure which disposes said blade structure in electrical contact with said spaced contacts.

GEORGE W. GOLDNER.
